UNITED STATES PATENT OFFICE.

GEORGE DAVIS, OF LYONS, NEW YORK.

DEVICE FOR WARMING BRIDLE-BITS.

SPECIFICATION forming part of Letters Patent No. 701,161, dated May 27, 1902.

Application filed February 3, 1902. Serial No. 92,441. (No model.)

To all whom it may concern:

Be it known that I, GEORGE DAVIS, a citizen of the United States, residing at Lyons, in the county of Wayne and State of New York, have 5 invented new and useful Improvements in Devices for Warming Bridle-Bits, of which the following is a specification.

It is well known that in cold weather bits attached to bridles hung up in the stable become 10 so cold that serious injury is often done to horses' mouths in placing these cold bits therein in bridling them.

The object of my invention is a device for warming or thawing out bits, and thereby 15 avoid injuring and frightening horses.

The novel construction used by me in carrying out my invention is fully described in this specification and claimed, and illustrated in the accompanying drawings, forming a part 20 thereof, in which—

Figure 1 is a perspective of a lantern with my device attached thereto and a bridle hanging thereon. Fig. 2 is a detail of the cap. Fig. 3 is a modified form of my device.

Like numerals of reference designate like 25 parts in the different views of the drawings.

The numeral 1 designates a lantern of ordinary construction, having a chimney 2. Mounted on the lantern 1 is a detachable cap 3, having an overhanging roof 4 and draft-openings 5. The cap 3 is provided with parallel indentations 6, adjacent to the edge of the roof 4, which are designed to serve to

support bits 7 of bridles 8. Curved guards 9 are mounted adjacent to the indentations 6 35 and serve to engage the bits 7 to hold them against slipping off. I may attach the cap 3 to lanterns or lamps of other forms than the one shown. In operation two bridles can be hung on at one time and will not interfere. 40

In the modified form curved guards 10 and slides 11, closing apertures 12, are provided. In heating the slides 11 are withdrawn to expose the bit directly to the heat of the flame.

I do not wish to be limited as to details of 45 construction, as these may be modified in many particulars without departing from the spirit of my invention.

Having described my invention, what I claim as new, and wish to secure by Letters 50 Patent, is—

The combination with a lantern, of a cap bearing an indentation designed to engage a bridle-bit and support it, there being an aperture in the bottom of said indentation, and a 55 slide closing said aperture and constructed to be withdrawn to expose said bit to the direct heat of the flame, substantially as described.

In testimony whereof I have hereunto set 60 my hand in presence of two subscribing witnesses.

GEORGE DAVIS.
